US00D980805S

(12) **United States Design Patent** (10) Patent No.: **US D980,805 S**
 Williams et al. (45) Date of Patent: **** Mar. 14, 2023**

(54) **MASSAGER CONTROL DISPLAY**(71) Applicant: **PlayMakar Inc.**, Fort Worth, TX (US)(72) Inventors: **Michael J. Williams**, Colleyville, TX (US); **Nathan Andrew Fox**, Fort Worth, TX (US); **Micah Daniel McKinney**, Decatur, TX (US); **Federico G. Vierheller**, Fort Worth, TX (US)(73) Assignee: **PlayMakar, Inc.**, Fort Worth, TX (US)(**) Term: **15 Years**(21) Appl. No.: **29/814,030**(22) Filed: **Nov. 2, 2021**(51) LOC (14) Cl. **13-03**

(52) U.S. Cl.

USPC **D13/162**(58) **Field of Classification Search**USPC D13/162, 164, 171; D24/215; D14/218

CLAIM

The ornamental design for a massager control display as shown and described.

DESCRIPTION

The sole FIGURE is a front elevation view of the massager control display showing our new design wherein all features shown are in a single plane and perpendicular to the line of sight.

Remaining views have no design elements, and thus are omitted.
